(57) **CLAIM**

We claim the ornamental design for a dialysis device connector, as shown and described.

DESCRIPTION

FIG. 1 is a perspective side view of a dialysis device connector showing our new design;

FIG. 2 is a right side elevation view thereof;

FIG. 3 is a left side elevation view thereof;

FIG. 4 is a right end elevation view thereof;

FIG. 5 is a left end elevation view thereof;

FIG. 6 is a top plan view thereof; and,

FIG. 7 is a bottom plan view thereof.

The broken lines show portions of the design that form no part of the claimed design.

The characteristic feature of the design resides in elongated body ending in a connector having threads.

1 Claim, 7 Drawing Sheets
